DUNCAN KENNER, OF NEW ORLEANS, LOUISIANA, BY COURT ORDER MRS. EMMA TUJAGUE KENNER SOLE HEIR AND LEGATEE OF DUNCAN KENNER, DECEASED

MOP HEAD

Application filed July 31, 1929. Serial No. 382,484.

This invention relates to mop heads or swabs, and has particular reference to an improved mop head of the type which is made up of a plurality of lengths of twisted strand-
5 ed material.

Mop heads or swabs of this type have been found to be open to certain objections, notably, the tendency of the strands to move over to one side of the wringer when the same 10 is passed through the wringer. After a careful analysis of the reason for this, it has been traced to the fact that the strands of a mop are twisted in the same direction and that in passing the strands through the wringer 15 rollers, an untwisting action is set up which tends to curve the strands in a direction opposite to the twisting.

It is, therefore, the outstanding object of the present invention to overcome this above 20 recited objection by producing a mop head composed of a group of lengths of stranded material, approximately one-half of which lengths have their strands twisted in an opposite direction to the other half and in which 25 the lengths are alternately arranged in the group so as to counteract the tendency of the strands to move laterally during the wringing operation.

As a still further object, the invention aims 30 to provide a mop in which the grouped lengths of stranded material, a portion of which is twisted in an opposite direction to the remainder, coact with each other to neutralize the untwisting tendency and therefore 35 minimize the fraying of the free ends.

Other objects of the invention reside in the production of an improved mop which does not materially increase the cost of production, while greatly adding to the efficiency 40 derived therefrom.

With the above recited and other objects in view, reference is had to the following description and accompanying drawings, in which there is exhibited one example or embodiment of the invention, while the claims define the actual scope of the same.

In the drawings:

Figure 1 is a front view of the mop head.
50 Figure 2 is a sectional view therethrough

taken approximately on the line 2—2 of Figure 1.

Referring to the drawings by characters of reference, the mop head or swab is designated generally by the reference character A and is made up of a plurality or group of lengths of stranded material, certain of which lengths B are twisted in one direction and the remainder of which lengths C are twisted in the opposite direction. The lengths of material 55 are suitably bound together in any desired manner, preferably by enclosing the intermediate portions thereof in a binding D so that the lengths are doubled to present eight portions E arranged within the binding with the remainder of the lengths free. In practice, the right and left-hand twisted lengths B and C are alternately arranged in side by side relation as illustrated, so that when the mop 60 head is passed through a wringer, it counteracts the tendency of the respective lengths to move laterally during the wringing operation and neutralizes the untwisting tendency by the coaction of the oppositely twisted lengths 65 with each other for the purpose of minimizing the fraying of the free ends. Due to this construction, it will be found that in addition to accomplishing a more thorough wringing 70 of the mop, the length of life and usefulness 75 of the same will be materially increased by the 80 minimizing of the fraying action.

What is claimed is:

1. A mop head composed of a group of lengths of stranded material, approximately one-half the number of which have the 85 strands twisted in an opposite direction to and toward the other half of said number.

2. A mop head composed of a group of lengths of stranded material, approximately one-half the number of which lengths have 90 the strands thereof twisted in an opposite direction to the other half of said number and in which the oppositely twisted lengths are alternately arranged in the group.

3. A mop head including a plurality of 95 lengths of stranded material arranged in side by side relation, in which the twists of the strands of alternately arranged lengths are disposed in opposite directions.

DUNCAN KENNER. 100
